UNITED STATES PATENT OFFICE

114,473

DESIGN FOR A VAPORIZING MACHINE

Louis F. Schmidt and Rheinhold Thur Schmidt,
Chicago, Ill., assignors to Miss O'Mist Products,
Inc., Chicago, Ill., a corporation of Illinois

Application February 20, 1939, Serial No. 83,106

Term of patent 7 years

To all whom it may concern:

Be it known that we, Louis F. Schmidt and Rheinhold Thur Schmidt, citizens of the United States, residing at Chicago, in the county of Cook and State of Illinois, have invented a new, original, and ornamental Design for Vaporizing Machines of which the following is a specification, reference being had to the accompanying drawings, forming part thereof.

In the drawings—

Figure 1 is a side elevational view of a vaporizing machine showing our new design.

Figure 2 is an elevational view of the same machine as seen from the left of Figure 1.

Figure 3 is a plan view of the machine shown in Figure 1.

Figure 4 is an elevational view showing the opposite side of the machine shown in Figure 1.

Figure 5 is an elevational view of the same machine as seen from the left of Figure 4; and

Figure 6 is a plan view, partly in cross section, of the base of the machine.

We claim:

The ornamental design for a vaporizing machine, substantially as shown.
